Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group composed of a circular wreath of flowers and leaves, having an opening through its center. This wreath contains the figure a, consisting of a rose with accompanying leaves; also, the figure b, composed of large circular flowers and their leaves; also, the branch c, projecting from figure b, consisting of star-shaped flowers, leaves, and sprays, and circling around to meet a branch projecting from the figure a. This group A is framed in by the band e, containing rosette-like figures, the band u, forming two steps, and the ornamented bands f, m, 25 D, and d.

The figure G consists of a bouquet of flowers

composed of two central roses surrounded by star-flowers, leaves, and sprays. This figure is framed in by the bands e i f l D, ornamented with various patterns.

The figure g is a fringe of mossy sprays projecting from the figure e.

The figure E consists of a bunch of circular flowers surrounded by leaves and with a stem bearing flowers and buds projecting, all framed in by the bands d, m, f, and e.

The figure F consists of a bunch of rose-like flowers, with their surrounding leaves resting on one side upon the figure h, containing a checkered ornamental pattern, and framed in by the bands f n i D.

The whole effect is that of a series of ornamental frames containing the flower-figures described.

I claim—

The design for carpets, consisting of group A, containing figures a, b, and c, figures E F G e d D l m f n h i, substantially as shown.
